SPRING BED BOTTOM, BED SPRING, OR
THE LIKE

Charles J. Elder, Brooklyn, N. Y., assignor to
Greenpoint Metallic Bed Co., Inc., Brooklyn,
N. Y., a corporation of New York

Application April 21, 1936, Serial No. 75,543

2 Claims. (Cl. 5—262)

This invention relates to spring bed bottoms, bed springs or the like and more particularly to means for stabilizing the movement of a top frame of a bed spring with reference to a bottom frame which, through interposed springs, support the top frame. An important object of the present invention is to provide novel and advantageous stabilizing means of the general character specified.

One important feature of the present invention involves the use at a desired position along a bed spring of a cross member which is spring supported from the bottom frame, and spring stabilizing devices interposed between the cross member and the upper frame, the spring stabilizing devices supported by the cross member being desirably weaker than the spring supports for the cross member whereby for light stresses the spring stabilizing devices substantially alone are adapted to give, although also there may be comparatively a very slight give to the spring supports for the cross-member, but these will yield to a greater extent under greater stresses imposed on the spring stabilizing devices, with the result that any up or down movement of such cross-member is minimized and is not as great as the up or down movement of the top frame.

These being among the objects, features and advantages of the present invention, the same consists of certain features of construction and combination of parts to be hereinafter described and then claimed with reference to the accompanying drawings illustrating a preferred embodiment of the invention and modifications of certain features, and wherein

Fig. 1 is a fragmentary view in vertical transverse section, parts being omitted across the view to enable it to be on a larger scale;

Fig. 2 is a fragmentary top plan view of the structure at one side of the spring, parts being omitted across the view to enable it to be on a larger scale;

Fig. 3 is a detail view on a larger scale illustrating one of the spring stabilizing devices and its connection with the corresponding cross member;

Fig. 4 is a fragmentary top plan view illustrating another form of supporting means for the cross member at the bottom of a stabilizing unit which is not shown in this view;

Fig. 5 is a section taken on the line 5—5 of Fig. 4;

Fig. 6 is a fragmentary view illustrating in elevation a third form of spring support for the cross member of the stabilizing means; and

Fig. 7 is a plan view of the structure illustrated in Fig. 6.

Referring to the drawings, the spring bed bottom comprises an upper frame 10 preferably composed of angle metal, a lower frame 11 which may also be formed of angle metal, and coil compression springs 12 interposed in a suitable manner between end bars 13 of the upper frame 10 and end ones of the cross bars 14 of the lower frame 11 as shown in Fig. 1 to assist in the support of the upper frame from the lower. The end bars of the lower frame 11 are suggested by the broken horizontal line at the left of Fig. 1, extending from that frame. Further support of the upper frame 10 from the lower frame is obtained by additional coil springs 12 which are within the two frames and are supported by additional cross-bars, such as 14, (Fig. 2), connecting the opposite side rails of the lower frame. Such use of coil springs, as 12, throughout a bed bottom or similar structure and supported on cross bars 14 is well known in the art and requires no further illustration.

Stabilization of the upper frame 10 with reference to the lower frame 11 may be effected by use of one or more stabilizing assemblages, two being illustrated in Fig. 2. According to the preferred embodiment of the invention illustrated in Figs. 1 and 2, each stabilizing assemblage comprises a cross member 15 connected at each end to a side of lower frame 11 by means of a heavy helical tension spring 16, and stabilizing means or devices supported on and above the ends of the cross member 15 and connected with the corresponding sides of the top frame 10.

Each of these stabilizing devices comprises an arm 17 rigidly connected at one end with one side of the upper frame 10 and extending downwardly and inwardly to a point adjacent to the corresponding cross member 15. The lower end of the arm 17 has a suitable spring tensioned connection with the adjacent end of the cross-member. As illustrated in Figs. 1, 2 and 3, said spring tensioned connection comprises a pair of links 18 and 19 of unequal length pivoted to the lower end of the arm and to the corresponding end of the cross member 15 (the longer link 18 being nearer the adjacent end of the cross-member than the shorter link 19), and a tension spring 20 connecting the upper pivot of the shorter link 19 with the lower pivot of the longer link 18. The tension springs 20 preferably are weaker than the springs 16. As indicated on Fig. 1 the lower ends of the arms 17 constitute stops that engage the upper edges of cross member 15

and limit upward movement of the top frame 10.

There should be stabilizing means at opposite sides of the two frames 10, 11, so that if a person should sit on one side of the bed and thus depress

5 the top frame 10, the stabilizing means at that side will act to restore the top frame to its predetermined upper position when such person's weight is removed. Upon thus depressing a side rail of the top frame the latter is tilted, with the

10 result that the flat under surface of such depressed rail, to which the arm 17 preferably is fixed, is somewhat upwardly inclined transversely from the outer edge of the rail, and this causes the angularity of the arm 17 to the horizontal to

15 be decreased, or the arm to be less inclined to the horizontal than when the top frame 10 is in its up-lifted position. In other words, the inner end of the arm 17 is moved away from the cross member 15 even if the arm is rigid as preferred, and,

20 as the said rail moves down substantially vertically, the inner end of the arm is moved away from the corresponding rail of the frame 11. At the same time, but after first partly depressing resiliently mounted member 15, the arm 17 ful-

25 crums on the upper pivot of longer link 18 and pushes back thereon, thus swinging back shorter link 19, and, inasmuch as the extreme inner end of the arm is now pushed in, in spaced relation to the cross member 15, the upper pivot of such

30 link 19 has put the spring 20 under the tension imposed by the weight of the person sitting on the corresponding side of the bed. As such person rises from sitting position the tension of the spring 20 and of springs 16 promptly restores

35 the elements of the stabilizer to the normal position shown in Fig. 1, and brings the frame 10 back to its original position, any further upward movement thereof being stopped by the extreme inner end of the arm 17, or the lower corner

40 thereof at that end, coming in contact with the cross member 15. The slight vertical movement of the cross member 15 relatively to the greater degree of depression of frame 10, and which cross member movement is afforded by the springs 16, is also of advantage as it means that the further

45 down the depressed side rail of the frame 10 goes after first somewhat depressing resilient cross member 15, the greater is the spacing between the extreme inner end of arm 17 and the cross member 15, the springs 16 and 20 acting together to restore the arm 17 and the top frame

50 to their normal positions in which the extreme inner end of the arm is brought into abutting relation with the cross member 15.

55 It will be evident that the stabilizing means hereinbefore described will be very effective in maintaining the proper relation between the top frame 10 and the bottom frame 11.

Referring to the modification shown in Figs. 4 and 5, the only substantial change from the stabilizing means of Figs. 1, 2 and 3 resides in the use, at each end of a slightly modified cross member 15a, of two tension springs 16a attached at their inner ends to the cross member 15a and diverging toward the adjacent side of the lower frame 11 to which they are secured. In the specific form shown the member 15a is twisted so

60 as to provide a horizontal portion at its ends which portion is provided at opposite sides of its middle line with perforations through which the ends of the springs 16a pass. Preferably the

65 other ends of these springs are connected with the ends of cross bars 14 of the lower frame 11. This arrangement tends of course to resist turn-

ing of the cross member 15a, thus holding the stabilizer such as 17 in an upright plane.

Referring to the modification illustrated in Figs. 6 and 7, it will be seen that it differs from that of Figs. 4 and 5 only in arranging springs 5 16b, diverging from the end of cross member 15b, in a vertical plane and in securing their outer ends to a vertical member 21 attached to the adjacent side of the lower frame 11.

In all forms of the invention the spring structure is adapted to be compressed into a narrow space as compared with the depth of the structure when the same is in using position, which permits a smaller package to be made for shipping or storage. 10

15 It should be understood that changes may be made in the construction and arrangement and that certain features may be used without others without departing from the true scope and spirit of the invention.

20 What I claim as new is—

1. In a bed spring or the like, the combination of a top frame and a bottom frame, springs supported from the bottom frame and acting on and supporting the top frame, a cross-member extending between opposite sides of the bottom frame and positioned between the lower ends of the supporting springs, the extremities of the cross-member terminating at points spaced inwardly from such opposite bottom frame sides, 25 tension springs connecting such extremities of the cross-member with such opposite sides, and stabilizing means above and supported on each end of the cross-member and between the tension springs and each such means including 30 arms inclined downwardly and inwardly from the top frame and attached to opposite sides thereof, a pair of links of different lengths pivoted to the lower end of each arm and pivotally connecting the links with the corresponding end 35 of the thus tensioned cross-member, the longer link being further out on the cross-member than the shorter link, and the links converging toward the arm, together with a tension spring connecting the upper pivot of the shorter link with the 40 lower pivot of the longer link. 45

2. In a bed spring or the like, the combination of a top frame and a bottom frame, springs supported from the bottom frame and acting on and supporting the top frame, a cross-member extending between opposite sides of the bottom frame and positioned between the lower ends of the supporting springs, the extremities of the cross-member terminating at points spaced inwardly from such opposite bottom frame sides, 50 helical tension springs connecting such extremities of the cross-member with such opposite sides, and stabilizing means above and supported on each end of the cross-member and including arms inclined downwardly and inwardly from the top frame and attached to opposite sides thereof, a pair of links of different lengths pivoted to the 55 lower end of each arm and pivotally connecting the links with the corresponding end of the cross-member, the longer link being further out on the cross-member than the shorter link, and the links converging toward the arm, together with a tension spring connecting the upper pivot of the shorter link with the lower pivot of the longer link, the lower ends of the arms constituting 60 stops, located inwardly of the shorter links, striking the cross member and limiting upward movement of the top frame. 65

CHARLES J. ELDER.
